UNITED STATES PATENT OFFICE.

JOHN Z. POLLARD AND GEORGE J. LEDERER, OF CHICAGO, ILLINOIS.

CHALK-SHARPENER.

1,186,830.

Specification of Letters Patent. Patented June 13, 1916.

Application filed January 19, 1914. Serial No. 813,105.

To all whom it may concern:

Be it known that we, JOHN Z. POLLARD and GEORGE J. LEDERER, citizens of the United States of America, and residents of 5 Chicago, county of Cook, and State of Illinois, have invented certain new and useful Improvements in Chalk - Sharpeners, of which the following is a specification.

This invention relates to automatic means 10 for sharpening tailors' chalk and the like. Heretofore it has been customary in the tailoring art to sharpen the chalk by hand requiring some degree of skill and judgment and usually entailing loss of the shavings.

15 The main objects of this invention are to provide improved means for sharpening chalk; and to provide an apparatus of this character which shall comprise a chalk holder and a cutter relatively movable past 20 each other; which shall produce a sharp uniform edge without breaking the corners at the ends of the chalk; which shall be automatic in its handling of the chalk; power driven with respect to the cutter; readily operable by any person without regard to skill, strength or experience; inexpensive 25 to manufacture and operate; accurate, durable and efficient in use, and saving of chalk material.

30 An illustrative embodiment of this invention is shown in the accompanying drawings in which—

Figure 1 is a top plan view of the device as a whole, with the top cover plate removed 35 and with part of the motor and the opposite side of the casing broken away. Fig. 2 is a horizontal section on the line A—A of Fig. 3 showing an underneath view of the runway and carriage. Fig. 3 is a vertical 40 longitudinal section through the upper part of the device on the line B—B of Fig. 1. Fig. 4 is a perspective view of the cover plate. Fig. 5 is a vertical transverse section of the device on the line C—C of Fig. 45 1. Fig. 6 is a vertical transverse section through the upper part of the device on the line D—D of Fig. 1. Fig. 7 is a vertical longitudinal section through the central upper part of the device on the line E—E of Fig. 50 Fig. 5. Fig. 8 is a perspective view of the guide cleaner. Fig. 9 is a plan view of one of the clamp jaws. Fig. 10 is a perspective view of a piece of chalk sharpened on two opposite edges. Fig. 11 is a plan view of the 55 jaw actuating control guides.

In the construction shown in the draw-

ings the device as a whole comprises mainly an upright box-like casing 1 having a support frame 2 partially covering the top and adapted to support the working mechanism, 60 a plate-like cover 3 of peculiar construction fitting upon said frame and closing said device, a runway 4 carried by the frame 2, a carriage 5 arranged for reciprocation on said runway, operating means 6 for controlling said carriage subject to the will of the operator, clamping means on said carriage for holding the chalk during the sharpening process, a tool 7 carried by said frame arranged and adapted to sharpen the chalk 70 when the device is operated, and motive means 8 carried by the said frame for operating said tool.

The casing 1 is of light, hollow construction and preferably contains a drawer 9 75 adapted to receive the shavings from the cutter, and which may be used also as a storage receptacle for chalk. A space 10 is provided between the drawer and the back of the casing for the lower end of the handle 6. A transversely and downwardly inclined collector chute 12 is provided within said drawer at one end, beneath where the chalk 13 is released and drops from the carriage. This chute comprises a grating of 80 spaced parallel wires or bars 14 inclined downwardly across the drawer to a slot 15 in the front for discharging the chalk after it is sharpened. The chalk-chips or shavings 16 drop through the bars and collect 85 in the bottom of the drawer. A suitable receptacle 17 is secured to the front of the drawer beneath said slot to receive the chalk as it is discharged from the chute.

The frame 2 may be of any suitable form 90 adapted for mounting the apparatus, but preferably comprises a horizontal plate portion 18 attachable to the top of the casing as by screws 19, said plate being open at its middle portion and provided with an upstanding inner peripheral flange 20. A bracket 21 adapted to support the motor 8 is also formed integral with the rear edge 100 of said frame.

The cover 3 is flat in general shape and 105 is formed to fit closely upon the frame flange 20 where it is removably secured as at 22 by suitable means such as screws or the like. This cover is provided with a central longitudinal depression 23 extending throughout 110 the greater part of its length, said depression being longitudinally slotted as at 24

at the middle of the plate and toward one end to receive and provide a passage way for chalk as it travels past the cutter. The edges of the slot 24 help to steady and guide the chalk. The said cover 3 is provided with a shield 26 substantially integral therewith and disposed in an arched position toward and over the end of said slotted depression which overlies the cutter. This shield serves 10 to stop flying chalk-chips and shavings and prevents dropping chalk or other objects into the slot over the cutter.

The runway 4 is disposed longitudinally of the open part of the frame 2 and comprises a pair of spaced parallel bars 30 removably secured at their ends to the vertical end flanges of said frame. This runway is substantially a part of the frame 2.

The carriage 5 comprises a rigid body member 33 of substantially flat oblong shape formed adjacent to its side edges with parallel slideways 34 to receive the runway bars 30 for support thereon, and is preferably made as a casting suitably formed and adapted to receive and support certain members carried thereby. A longitudinal slot 36 is provided in the front end of the carriage in registry with the cover slot 24 to receive the flat strips or sections of chalk 30 to be sharpened. A clamp is provided adjacent to this slot for rigidly securing the chalk in place. This clamp is preferably disposed on the under side of the carriage, and comprises a pair of flat rectangular jaw plates 39 disposed side by side in the same plane and having opposing edges 40 of saw tooth shape adapted to interfit when brought together. These jaws 39 are disposed in transverse grooves 42 in the under side of 40 the carriage body 33 and adjacent to the front end, and are arranged to reciprocate transversely of the carriage. Two operating levers 43, arranged as a coacting pair, support said jaws. Said levers are disposed 45 in substantially parallel relation on opposite sides of the carriage beneath the jaws, and are pivoted directly to the rear portion of the carriage, preferably at points adjacent to their inner edges, as at 45. The 50 forward arms 46 of said levers are normally urged together by yieldable means as a spring 48 preferably comprising a U-shaped rod disposed on the under side of said levers with its ends pivotally connected as at 49 to the forward ends thereof. The rearward arms 50 project back of the carriage. The closure of said jaws is limited by stops 51 fixed on the under side of the carriage body 55 adapted to engage the forward arms of said levers, and limit the inward movement thereof. Each of the jaws is secured to its support arm 46 by means of a pivot 52 passing through the middle portion of the jaw, adapted to permit such oscillation of the 60 jaw as is provided for by the groove 42

in which the jaw is seated. Jaw closing control guides are provided on the frame 2 at the rear end and comprise preferably a pair of forwardly projecting lugs or studs 53 on the inner side of the rear frame flange. 70 When the carriage is withdrawn to its normal inoperative position at the rear end of the runway the rearward arms 50 engage the inner or opposing faces 54 of said studs. These studs toward their forward ends are 75 divergent so that when the carriage advances the coacting arms are permitted to move apart according to the inclination of said opposing faces 54, thus providing for 80 gradual closure of the jaws on the forward arms. The extreme rear portions of these faces are parallel as at 55 and are spaced only enough to receive the lever arms 50. Vertically pivoted bearing rollers 57 are carried by the arms 50 to avoid friction with 85 said faces.

The cutter 7 comprises a rotatable hub 60 and a plurality of blades 61 formed and arranged in any suitable manner thereon to give the desired form to the chalk. It is 90 preferably formed with an annular series of pairs of radial blades with cutting edges on adjacent opposing sides, said cutting edges being convergent toward the axis of the cutter, as shown at 62 on Fig. 5, these 95 blades being adapted to produce a double beveled and more or less sharp edge to the chalk depending upon adjustment of certain parts, as it passes through the cutter between said blades. The cutter is secured 100 by a nut 63 to the inner end of a shaft 64 journaled in the frame 2 and connected directly to the motor 8. As the carriage 5 is moved forward it passes over the revolving cutter and carries the chalk in proper 105 operative relation thereto for sharpening.

The cutter is arranged for the motion of the blades to be codirectional with the chalk when cutting but at far greater speed. The cutting stroke is thus upward and forward. 110 By this means the cutting force always acts toward the body of the chalk and there is no tendency to break away the corners of the chalk.

Clamp releasing means are provided consisting of a pair of toggle members or links 115 connecting the forward ends of the lever arms 46. Said toggle links are pivoted together at their adjacent ends and incline rearwardly when the jaws are closed. When 120 the carriage reaches the forward limit of its travel the forwardly projecting links 65 are forced against the forward flange of the frame 2, and are forced into alignment with each other as the carriage is urged 125 forward, until the connecting pivot 66 passes the critical point, whereupon the toggle becomes locked in its open position and the jaws are thereby held open until the toggle is released. The inner ends of the links 130

when set bear against the forwardly projecting stop shoulders 67 on the carriage. When the jaws are thus opened the chalk escapes and passes down the chute into the receptacle. The carriage is then withdrawn to its normal position ready to receive another piece of chalk.

Clamp closing means comprise a dog 69 on the inner side of one of the side flanges 10 of the frame for releasing the toggle, in combination with said guide studs 53 on the rear frame flange which retard the closure. Said dog is so disposed as to permit the carriage to move backwardly without affecting the toggle, but will engage an outwardly projecting arm 70 of one of the toggle links and release the toggle as soon as the carriage has begun to move forward, this permitting the spring 48 to set the clamp upon the chalk as soon as the rear ends of the clamp levers advance past and from the control guides 53.

Gage means are provided for adjusting the degree of sharpness to be given to the 25 edge of the chalk. This gage comprises a vertically movable member 73 having a longitudinal guide groove 74 therein arranged in alinement with the cutter 7 and is adapted to receive the lower edge of the chalk. 30 Any suitable means may be provided for raising and lowering said member 73, but vertical guide 76 on the frame and coacting means 77 on the gage member together with an adjusting screw 78 arranged for moving the member 73 up and down, are found to be well adapted for the purpose. The screw 78 passes freely down through a rigid lug 79 on the frame flange 20 and engages a threaded perforation in the member 73. 40 A spring is provided to urge the guide member downwardly against the action of the adjusting screw and is preferably disposed in helical form about the said screw.

A gage groove cleaner is provided on the 45 rear end of the carriage and comprises a bracket like integral member having a perforated shank 81 adapted to fit against the under side of the carriage and a downwardly projecting finger 82 formed to pass 50 readily through the guide groove in the gage member 73 and to remove all chalk, shavings or other material therefrom in so doing. Said shank is secured to the carriage by means of a screw 83 or the like adapted 55 when loose to permit lateral adjustment of the cleaner for centering the finger with the guide groove 74, and when set to hold the cleaner rigidly in place on the carriage.

Driving means for the cutter may comprise any suitable motor or driving force, but an electric motor 8 is preferred, said motor being mounted on the frame bracket 21 in alinement with and suitably connected to the cutter shaft.

60 In order to facilitate oiling the apparatus

the cover 3 is provided with perforations immediately over the several points where oil is required, each of the oil perforations being indicated by any suitable means. A suitable oil pad is attached to the front ends 70 of the runway bars within reach of the forward end of the carriage when the latter is moved to its forward position, thereby assuring thorough lubrication of the runways at all times.

75 The operation of this improved chalk sharpener is as follows: The motor is started in the ordinary manner. Assuming that the carriage is at the rear end of the runway and that the jaws are open, a piece of chalk is dropped edgewise into the cover slot. The carriage is then moved forward by means of the handle thereby causing the jaws to close upon the chalk by gradual movement of the lever arms as they are released by the inclined guide shoulders on the rear of the frame. Simultaneously with the beginning of movement of the carriage forward, the toggle joint is released by means of engagement of one of the toggle 80 arms with the dog, thus leaving the closure of the jaws under control of the spring and operating lever. As soon as the jaws are set upon the chalk the front end of the carriage arrives at the cutter, whereupon the sharpening process begins and continues until the chalk is moved entirely past the cutter. Shortly after the carriage passes the cutter, the forward ends of the toggle links contact with the rigid frame and the 85 toggle links are forced laterally into alinement, thus releasing the jaws and permitting the chalk to drop onto the chute from whence it is delivered by gravity to the receptacle at the front of the casing. The 90 shavings also drop upon the chute, but pass through the grating and are collected in the bottom of the drawer. When the toggle links contact with the rigid frame and the toggle links are forced laterally into alinement, thus releasing the jaws and permitting the chalk to drop onto the chute from whence it is delivered by gravity to the receptacle at the front of the casing. The 95 shavings also drop upon the chute, but pass through the grating and are collected in the bottom of the drawer. When the toggle links contact with the rigid frame and the toggle links are forced laterally into alinement, thus releasing the jaws and permitting the chalk to drop onto the chute from whence it is delivered by gravity to the receptacle at the front of the casing. The 100 shavings also drop upon the chute, but pass through the grating and are collected in the bottom of the drawer. When the toggle links contact with the rigid frame and the toggle links are forced laterally into alinement, thus releasing the jaws and permitting the chalk to drop onto the chute from whence it is delivered by gravity to the receptacle at the front of the casing. The 105 shavings also drop upon the chute, but pass through the grating and are collected in the bottom of the drawer. When the toggle links contact with the rigid frame and the toggle links are forced laterally into alinement, thus releasing the jaws and permitting the chalk to drop onto the chute from whence it is delivered by gravity to the receptacle at the front of the casing. The 110 shavings also drop upon the chute, but pass through the grating and are collected in the bottom of the drawer. When the toggle links contact with the rigid frame and the toggle links are forced laterally into alinement, thus releasing the jaws and permitting the chalk to drop onto the chute from whence it is delivered by gravity to the receptacle at the front of the casing. The 115 shavings also drop upon the chute, but pass through the grating and are collected in the bottom of the drawer. When the toggle links contact with the rigid frame and the toggle links are forced laterally into alinement, thus releasing the jaws and permitting the chalk to drop onto the chute from whence it is delivered by gravity to the receptacle at the front of the casing. The 120 shavings also drop upon the chute, but pass through the grating and are collected in the bottom of the drawer. When the toggle links contact with the rigid frame and the toggle links are forced laterally into alinement, thus releasing the jaws and permitting the chalk to drop onto the chute from whence it is delivered by gravity to the receptacle at the front of the casing. The 125 shavings also drop upon the chute, but pass through the grating and are collected in the bottom of the drawer.

Although but one specific embodiment of this invention has been herein shown and described, it will be understood that numerous details of the construction shown may be altered or omitted without departing from the spirit of this invention as defined by the following claims.

We claim:—

1. In a chalk sharpener, the combination 130

of a base, a clamp mounted for relative movement thereon, clamp closing means comprising a pair of parallel levers having relatively stationary fulcrum means, yielding means connected for urging the forward arms of said levers together, toggle means connecting said forward arms for holding the same apart, a dog on said base for releasing said toggle means, and a pair of stationary shoulders on said base having inclined opposing faces arranged to coact with said levers to provide for gradual release of the levers.

2. In a chalk sharpener, a frame having a runway thereon in combination with a carriage for reciprocating on said runway, clamping means on said carriage comprising a pair of arms pivoted at one end adjacent to the rear end of the carriage, means normally urging the free ends of said arms together, toggle means connecting the free ends of said arms, said toggle means being set by contact with said frame when the carriage is moved to its extreme forward limit to hold said arms apart, and a dog carried by said frame for releasing said toggle as soon as the carriage begins its forward movement.

3. In a chalk sharpener of the character described, a reciprocatory carriage for the chalk to be sharpened in combination with

a cutter disposed beneath the forward part of the path of said carriage, and a gage member disposed beneath the rear portion of the path of said carriage, said gage being vertically adjustable and adapted to determine the vertical position of the chalk in the carriage, substantially as and for the purpose set forth.

4. A chalk sharpening machine comprising a frame, a carriage mounted to reciprocate on said frame, a pair of clamp bars arranged side by side and having two adjacent ends pivoted to said carriage, coacting jaws borne by the opposite ends of said bars respectively to grip the chalk, a pair of bars arranged for toggle action pivoted together at adjacent ends and at their opposite ends pivoted to the jaw bearing ends of said clamp bars, and means on said frame to set the toggle when the carriage is moved to one position and to release the toggle when the carriage is moved to another position respectively.

Signed at Chicago this 27th day of August 1913.
